BELT CONVEYER FOR NEWSPAPERS AND
LIKE ARTICLES

Harold Herbert Rapley, Bedford, England, assignor to Cutler-Hammer, Inc., Milwaukee, Wis., a corporation of Delaware

Application September 25, 1936, Serial No. 102,496
In Great Britain October 1, 1935

2 Claims. (Cl. 198—165)

This invention relates to belt conveyers for newspapers and like articles and refers more particularly to those arrangements in which the conveyer has to turn a corner say from the horizontal to the vertical.

In such arrangements, difficulty has been heretofore experienced in that the papers have had a tendency to jam at the bend and also in that a sliding or "sawing" effect has been produced owing to the velocity of the surface of the papers on the outside of the bend being greater than that on the inside.

It is the object of the present invention to provide an improved cornering system in which these difficulties are overcome, and the invention consists broadly in the arrangement that a cornering belt, running in a direction between that of the two main runs, is provided for engaging the surface of the papers or the like on the outside of the bend, said cornering belt having its centres spaced apart to ensure flexible contact with the stream of papers regardless of the thickness of the latter, and being not positively driven so that it adjusts its speed to that of the outer surface of said stream.

In order that the invention may be the more clearly understood an arrangement in accordance therewith will now be described reference being made to the accompanying drawing.

In this arrangement the newspapers are conveyed round a corner from the horizontal to the vertical direction, the horizontal conveying being effected between upper and lower horizontal belts 1 and 2 and the subsequent vertical conveying between inner and outer vertical belts 3 and 4.

The upper horizontal belt 1 and the inner vertical belt 3 have a common end roller 5 and, fairly close to said end roller, respective guide rollers 6 and 7, the guide rollers being close to the respective lower horizontal belt 2 and outer vertical belt 4, and the common end roller 5 being off set inwardly from said lower horizontal belt 2 and said outer vertical belt 4. Thus the ends of the upper horizontal belt 1 and inner vertical belt 3 turn away from the horizontal and vertical respectively and meet each other at an obtuse angle of say 130° to 140°. In rounding the corner the papers are held against these turned ends of the upper horizontal belt 1 and inner vertical belt 3 by means of a cornering belt 8 running over free end rollers 9 and 10 and whose operative run is at an angle to say 45°.

The non-operative run of this cornering belt 8 passes over a free roller 14 and said belt is thus

driven solely by frictional engagement with the stream of papers.

With this arrangement, the papers pass first between the upper horizontal belt 1 and the lower horizontal belt 2 as far as the guide roller 5 of the said upper horizontal belt 1 and the cornering belt 8 as far as the common roller 5 of the upper horizontal belt 1 and inner vertical belt 3; then between said inner vertical belt 3 and said cornering belt 8 as far as the guide roller 7 of said inner vertical belt 3, and finally between said inner vertical belt 3 and the outer vertical belt 4.

Thus, instead of turning at a sharp angle, the papers make a turn in three stages or, in effect, on a fairly wide curve, and thus any tendency to jamming is avoided. Moreover since the cornering belt is driven solely by frictional engagement with the stream of papers it is free, when papers are passing, to conform its speed to that required by said papers, either faster or slower according as a thick or thin layer is passing. Thus the tendency to the sliding or "sawing" of the papers is obviated.

The numerals 12 and 13 designate small inks pivoted at one end and carrying the rollers 9 and 10 at the other. Thus the distance apart of the rollers 9 and 10, and therefore the tension of the belt 8 and its proximity to the roller 5 can be varied.

It will be obvious that the arrangement described can be equally well employed for conveying papers from the vertical to the horizontal direction. In either case the upper horizontal belt 1 will usually only be required to extend a very short distance from the corner—only far enough in fact to ensure that it performs its cornering function as described. In a few cases however, as when the conveyer is exposed to strong draughts, it may be preferred to continue the upper horizontal belt 1 the full length of the lower horizontal belt 2.

It will be appreciated that the belts referred to in the foregoing description are actually composite belts each consisting of a plurality of component wire belts, and the rollers referred to consist each of a number of pulleys over which said component belts run. Where a common roller is referred to, it will comprise pulleys for the component belts of both the composite belts running over it.

What I claim and desire to secure by Letters Patent is:—

1. In a newspaper conveyer, in combination, associated horizontal and vertical belt conveyer

sections for carrying the newspapers in overlapped relationship, the latter conveyer section including inner and outer belts between which the newspapers are frictionally held, driving 5 rollers for said belts including a corner roller associated with said inner belts for engaging the inner surface of the newspapers as the same pass around the corner between said conveyer sections, and auxiliary belts arranged between 10 said outer belts and crossing the angle between said conveyer sections for engaging the outer surface of the newspapers as the same pass over said corner roller, said auxiliary belts being driven solely by frictional engagement with the outer 15 surface of the newspapers and acting to yieldingly hold the same in engagement with said corner roller.

2. In a newspaper conveyer, in combination,

associated horizontal and vertical belt conveyer sections for carrying a stream of newspapers in overlapped relationship, said vertical conveyer section including inner and outer endless belts between which the newspapers are frictionally held, spaced inner and outer corner rollers located between said conveyer sections and associated with said inner and outer belts, and auxiliary endless belts passing between said corner rollers and crossing the angle between said conveyer sections for engaging the outer surface of the newspapers as the same pass over said inner corner roller, said auxiliary belts being driven solely by frictional engagement with the outer surface of the newspapers and acting to yieldingly hold the newspapers in engagement with said inner corner roller. 5 10 15
